UNITED STATES PATENT OFFICE.

FRANCIS D. HALSTEAD AND LEON C. ANDREWS, OF LOCK HAVEN,
PENNSYLVANIA.

FURNACE-ROOF.

No. 852,835.

Specification of Letters Patent.

Patented May 7, 1907.

Application filed January 31, 1907. Serial No. 856,115.

To all whom it may concern:

Be it known that we, FRANCIS D. HALSTEAD and LEON C. ANDREWS, citizens of the United States, residing at Lock Haven, in the county of Clinton and State of Pennsylvania, have invented new and useful Improvements in Furnace-Roofs, of which the following is a specification.

Our invention pertains to furnace roofs; and it has for one of its objects to provide a furnace roof comprising metal and refractory material, and embodying such a construction that the refractory material is held under yielding pressure in proper position relative to the metal, this in order to compensate for unequal expansion and contraction of the metal and refractory material so as to prolong the usefulness of the latter, and also to hold the refractory material in place and prevent the entire arch thereof from falling when the sections of refractory material wear away either by melting or chipping off.

Another object of the invention is the provision of a furnace roof constructed in such a manner that it may be expeditiously and easily refined with refractory material when necessity demands so as to prolong its usefulness as a whole for an indefinite period.

Other advantageous characteristics peculiar to our invention will be fully understood from the following description and claims when the same are read in connection with the accompanying drawings, forming part of this specification, in which:

Figure 1 is an elevation of a portion of a furnace roof constructed in accordance with our invention. Fig. 2 is a detail plan view of one end of the said roof portion. Fig. 3 is an elevation of the outer side of one of the clamps of the roof portion. Fig. 4 is a transverse section taken in the plane indicated by the line 4--4 of Fig. 1.

Similar letters designate corresponding parts in all of the views of the drawings, referring to which:

A is the metal frame or bung of our novel furnace roof portion. The said frame or bung is preferably, though not necessarily, of I-form in cross-section, Fig. 4, and provided at its ends with apertured reduced portions *a* on which are upwardly extending abutments or shoulders *b*.

B is the refractory material of the roof portion, which is preferably made up of a plu-

rality of bricks *c* arranged side by side and disposed under the frame or bung A throughout the length thereof, and C are the clamps which have for their office to hold the refractory material B in proper position relative to the frame or bung A. The said clamps C are provided with apertured lugs *d* to receive bolts *e* through the medium of which they are connected in a hinged manner to the reduced ends *a* of the frame or bung A; and they are also provided in their upper arms *f* with apertures *g* and *h*, as best shown in Fig. 3. For the sake of lending strength to the said clamps C they are preferably provided with ribs *i* on their backs as also best shown in Fig. 3.

D are devices through the medium of which the lower arms of the clamps C are held under yielding pressure against the ends of the refractory material B. These devices D are identical in construction, and therefore a detailed description of the one shown in Fig. 2 will suffice to impart a definite understanding of both. The said device D, Fig. 2, comprises headed and threaded bolts *m* extending outward through the apertures *h* of the clamp C, an abutment *n* loosely receiving the outer portions of the bolts *m* and having a central aperture, nuts *p* mounted on the threaded portions of the bolts at the outer side of the abutment *n*; an endwise movable rod *r* extending loosely through the aperture in the abutment *n* and the aperture *g* in clamp C and arranged to bear at its inner end against the frame abutment *b*, and having an enlargement *s* at an intermediate point of its length, and a coiled spring *t* surrounding the rod *r* and interposed between the enlargement *s* thereof and the adjustable abutment *n*. The said spring *t* serves to hold the rod *r* under yielding pressure against the shoulder or abutment *b* of the frame or bung A, and by adjusting the abutment *n* the tension of the spring *t* may be regulated as occasion demands.

By virtue of the devices D being constructed and arranged relative to the frame A and clamps C, in the manner illustrated and described, it will be apparent that the rods *r* held under yielding pressure against the shoulders or abutments *b* of frame A will serve to yieldingly press the lower arms of the clamps inward so as to enable said lower arms to yieldingly hold between them the

bricks *c* of refractory material. It will also be apparent that the spring-pressed clamps *C* will allow for unequal expansion and contraction of the metal frame *A* and refractory material *B* and tightly hold the bricks of refractory material at all times; and further, that the spring-pressed clamps will take up or compensate for wear of the bricks *c* and in that way tightly hold the refractory material notwithstanding such wear. It will further be appreciated from the foregoing than when the refractory material *B* is worn away to a considerable extent, the clamps *C* permit of the said refractory material being expeditiously and easily removed and as readily replaced with new refractory material so as to materially prolong the usefulness of the roof portion as a whole.

We prefer to employ the devices *D* for holding the clamps *C* yieldingly against the refractory material, but we do not desire to be understood as confining ourselves to the said devices *D* or to any specific arrangement of springs for accomplishing such purpose, inasmuch as the clamps *C* may be yieldingly held against the refractory material in any approved manner without involving departure from the scope of our invention as defined in the appended claims.

In addition to the practical advantages hereinbefore ascribed to our novel furnace roof or roof portion, it will be noted that the said roof or roof portion is simple, inexpensive and compact in construction, and that its metallic elements are well adapted to withstand the usage to which furnace roofs are ordinarily subjected.

Having described our invention, what we claim and desire to secure by Letters-Patent, is:

1. In a furnace roof, the combination of a metallic frame, clamps connected at an intermediate point of their length in a hinged manner to the frame and having lower arms arranged to receive and hold refractory material between them, and springs coöperating with the upper arms of the clamps for hold-

ing the lower arms thereof under yielding pressure against the refractory material.

2. In a furnace roof the combination of an arched metallic frame, bricks of refractory material arranged in an arched manner against the under side of the frame, clamps connected at an intermediate point of their length in a hinged manner to the frame and having lower arms to hold the bricks, and springs coöperating with the upper arms of the clamps to press the lower arms thereof against the bricks.

3. In a furnace roof, the combination of a metallic frame, bricks of refractory material arranged against the under side of the frame, clamps connected at an intermediate point of their length in a hinged manner to the frame and having lower arms for exerting pressure against the bricks, abutments carried by the upper arms of the clamps, rods movable through said upper arms of the clamps and arranged to bear against the frame, and springs interposed between the abutments and the said rods.

4. In a furnace roof, the combination of a metallic frame, bricks of refractory material arranged against the under side of the frame, clamps connected at an intermediate point of their length in a hinged manner to the frame and having lower arms for exerting pressure against the bricks, threaded bolts extending outward from the upper arms of the clamps, abutments movable on said bolts, nuts mounted on the bolts back of the abutments, rods guided in the upper arms of the clamps and arranged to bear against the frame, and springs interposed between the abutments and said rods.

In testimony whereof we have hereunto set our hands in presence of two subscribing witnesses.

FRANCIS D. HALSTEAD.
LEON C. ANDREWS.
